specification for Design.

Patented Feb. 7, 1922.

Application filed April 25, 1921. Serial No. 464,459. Term of patent 14 years.

To all whom it may concern:

Be it known that I, SAMUEL M. MUND, a citizen of the United States, residing at St. Joseph, in the county of Buchanan and State of Missouri, have invented a new, original, and ornamental Design for Hat Creasers, of which the following is a specification, reference being had to the accompanying drawing, forming a part thereof.

Figure 1 is a perspective view of the hat creaser, constituting my new design.

Figure 2 is an end elevation thereof.

Figure 3 is a side elevation of the same.

What I claim is:

The ornamental design for a hat creaser, as shown.

SAMUEL M. MUND.
